UNITED STATES PATENT OFFICE

1,943,556

SYSTEM FOR RECORDING SOUND

Oscar A. Ross, New York, N. Y.

Application September 18, 1928
Serial No. 306,655

15 Claims. (Cl. 179—100.3)

This invention refers to systems for synchronously photographically recording sound and action on films, and more particularly to that class more generally known as "talking movies".

5. When recording the speech of actors during the simultaneous recording of the action, either jointly on one film or on separated films, it is customary to gage the amplitude of the recorded sound by the sound volume characteristics of a 10. loud speaker in a monitor room, the acoustic characteristics of which are preferably proportioned to the acoustic characteristics of a theatre or theatres in which the recorded sound and action are to be finally presented. To build a 15. separate monitor room for each type of theatre now in general use would entail prohibitive expense and therefore a monitor room of general average acoustic characteristics must be chosen.

Furthermore, actors' voices vary considerably 20. in vocal characteristics, each requiring a preferred modulated circuit between the microphone and light valve recording the sound impulses onto the film.

On of the objects of this invention is to provide a system of recording sound and action simultaneously whereby a plurality of sound records of varying amplitude are simultaneously recorded on separated films, in this manner permitting the selection of a sound record of ideal 30. amplitude for the particular theatre in which it is to be presented, or the choice of a sound record of proper amplitude for general use, if the operator of the monitor room has erred in his judgment as to the proper amplitude for the 35. recording of the normal sound record.

Another object is to furnish means for recording a single sound record through a plurality of variably modulated circuits whereby the voices of actors having varying voice characteristics 40. may be recorded in chronological order on the same sound track, each of an amplitude whereby the reproduced records will render a pleasing and well balanced vocal presentation in synchronism with the action of the motion picture 45. presentation.

Other objects and advantages will appear as the description of the invention progresses, and the novel feature of the invention will be pointed out in the appended claims.

50. This invention consists in a novel construction and arrangement of parts hereinafter described, delineated in the accompanying drawing, and particularly pointed out in that portion of this instrument wherein patentable novelty is claimed for certain and peculiar features of the sys-

tem, it being understood that, within the scope of what hereinafter thus is claimed, divers changes in the form, proportions, size and minor details of the structure may be made without departing from the spirit of, or sacrificing any of the details of the invention.

In describing the invention in detail, reference is had to the accompanying drawing, wherein I have illustrated embodiments of my invention, and, wherein like characters of reference, designate corresponding parts throughout the several views, and in which:

Figure 1 is a diagrammatic view of one form of the invention, and Fig. 2 is also a diagrammatic view of a modified form of the invention.

Referring to Fig. 1, actors S, M and L are assumed to be speaking intermittently into microphones 1S, 1M and 1L, during the recording of "talking" motion picture production each actor having small, medium and large voices, respectively.

The microphones 1S, 1M and 1L each have a variable amplifying device as 2S, 2M and 2L in the circuit thereof, each circuit being independently controlled by a circuit closer as 3S, 3M and 3L adjacent said actors, whereby any one or all the circuits may be closed at will for definite and variable periods of time.

Each microphone circuit also includes known translating devices 4—4 and light valve units 5—5 supported by sound recording cameras 6A, 6N and 6S having raw negative ribbon film therein arranged to be advanced by rotation of shaft 7 driven by motor 8, said shaft also driving motion picture camera 9.

Each light valve unit, as 5, is arranged to control passage of light rays from lamp or light source 10 to said film, in the circuit of which is arranged a rheostat 11, the resistance 12 of which may be cut in or out by contact lever 13.

Referring to Fig. 2, the same actors S, M and L are assumed to be speaking into a single microphone 40, in the circuit of which are included in multiple a plurality of variable amplifying devices as 2S, 2M and 2L and a plurality of circuit closers, as 3S, 3M and 3L, said circuit also including light valves as 5—5 similar in function and similarly supported in cameras 6A, 6N and 6S, said cameras also supporting similar light sources, as 10, the circuit of said sources including a variable resistance rheostat, as 12—12, controlled by a lever, as 13.

1S microphone circuit

Referring to Fig. 1, assuming actor S is speak-

ing, the director or an assistant operator de-
presses circuit controller 3S, whereupon a cir-
cuit to microphone 1S is established as follows:—

- From positive energy, wire 25, circuit con-
troller 3S, wire 26, lever 27, 1 section of resist-
ance 28, wire 29, microphone 1S, wire 30 to
amplifying device 4 and thence to negative
energy, said amplifying device in known manner
amplifying the electrical oscillations in that por-
tion of the circuit including light valve units
5—5, said circuit flowing from device 4 to wire
31, thence through said light valves in series,
and thence returning to said amplifying device
through wire 33.
- In addition to supplying energy to light valve
units 5—5, each amplifying device, as 4, also
supplies energy to a loud speaker 21 in the
monitor, or control room 32, and the character
of the sound produced thereby is assumed to be
substantially the same as the sound subsequently
reproduced from the sound record photographically
impressed on the film in sound recording
camera 6N, in response to energy impulses from
microphone 1S, when and as a positive film pro-
duced therefrom is caused to reproduce said
sounds. In other words, said camera is record-
ing normal sound records assuming the judg-
ment of the operator of the monitor room who
is further assumed to be listening to loud
speaker 21, has been correct in modulating the
circuits to the microphones and light valve units.

It will be noted that one-half the resistance
12 is included in the circuit to light source 10
of sound recording camera 6N, it being assumed
that such adjustment furnishes sufficient illumi-
nation for the aforesaid normal sound recording
by light valve unit 5 of said camera.

It is to be further noted that lever 13 of sound
recording camera 6A has all the resistance 12
cut out whereby light source 10 therein is pro-
ducing abnormal illumination, in this manner
producing the recording of an abnormal ampli-
tude sound record on the film in said camera,
and it will be still further noted that the lever
13 of sound recording camera 6S is positioned
to include all of resistance 12 whereby a sub-
normal illumination will be produced in light
source 10 of said camera, in this manner pro-
ducing the recording of a subnormal amplitude
sound record on the film therein.

From the foregoing it is therefore obvious that
when the circuit controller 3S is depressed, and
actor S speaks into microphone 1S, that his
speech is recorded by each of sound recording
cameras 6A, 6N and 6S, camera 6A recording
an abnormal amplitude sound record, camera
6N, a normal record, and camera 6S, a subnormal
amplitude record. Therefore if the operator in
the monitor room has erred in his judgment of
normal recording, the developed negative from
sound recording camera 6A or 6S may be em-
ployed for printing of normal positive, depend-
ing upon which manner he has erred.

Assume that actor S has completed his "lines",
and that actor M is to speak, the operator
will release circuit controller 3S and depress
circuit controller 3M, thereby establishing a sim-
ilar hereuntofore described circuits to microphone
1M, and sound recording cameras 6A, 6N and
6S controlled thereby, and said cameras will like-
wise cause recording of abnormal, normal and
subnormal amplitude sound records on the films
therein, and, assuming further that actor M has
completed his lines and that actor L is to speak,
the operator will release circuit controller 3M

and depress controller 3L, whereby camera 6A,
6M and 6S, controlled by microphone 1L, will
similarly record the three differentiated ampli-
tude sound records upon the film therein.

It will be noted that whereas the circuit to
microphone 1S has only one section of resist-
ance 28 in series therewith, the microphone
1M has two such sections and microphone 1L has
three of such sections, it being understood that
the comparatively greater supply of energy
to microphone 1S will effect a recording of
sound waves, which when reproduced will be
of substantially the same loudness, or amplitude,
as the similar reproduced waves recorded by
microphone 1M, and that likewise, the compara-
tively reduced amount of energy to microphone
1L will effect a sound wave recording, which
when reproduced, for exhibition thereof, will be
of substantially the same loudness, or volume, as
similar waves produced by reproduction of sound
waves recorded by microphone 1M. In other
words, although the voices of actors S, M and L
may vary in amplitude as directed into the
microphones as 1S, 1M or 1L, when reproduced
by suitable positive prints from selected negatives
of cameras 6A, 6N and 6S, they will all appear to
have a uniform amplitude.

Referring to Fig. 2, showing a modification of
the system shown in Fig. 1, the three actors
S, M and L are assumed to be intermittently
speaking into the single microphone 40. When
actor S is talking, circuit closer 3S is depressed
and energy to said microphone will be supplied
from positive energy to wires 41 and 42, circuit
closer 3S, wire 26, rheostat lever 27, thence
through 1 section of resistance 2S, to wires 43
and 44, thence to microphone 40 and wire 45 to
amplifying device 4, and thence through wire 46
to negative energy, the amplified electrical oscil-
lations traveling from said device through wires
47 to light valve units 5—5 of sound recording
cameras 6A, 6N and 6S, in series and thence
through wires 50—50 returning to said device,
said cameras recording the sound waves in ab-
normal, normal and subnormal form as herein
described in connection with Fig. 1.

When actor M is to speak, circuit closer 3M is
depressed and the circuit to microphone 40 is
established through rheostat 2M, two sections
of which are in series, thence through wires 51
and 52 completing the circuit as described when
circuit closer 3S is closed.

When actor L is to speak, circuit closer 3L is
depressed, the energy flowing through three sec-
tions of rheostat 2L and thence through wires
53 and 52 and thereafter completing the circuit
as described when circuit closer 3S was depressed.

From the foregoing it will be noted that when
actor S with the smaller voice is speaking, micro-
phone 40 is rendered more receptive to sound
waves, whereas when actor M having a medium
voice is speaking, said instrument is rendered
less receptive and still less receptive when actor
L having a loud or large voice is speaking, and
that by thereby fixedly varying the receptive pro-
portion of said instrument to suit each actor, a
more accurate recording of the sound waves
therefrom may be obtained.

It is also to be noted that as each actor as S,
M or L, is speaking a triple sound record is made
by cameras 6A, 6N and 6S, one record being re-
corded as normal, another as abnormal and the
third as subnormal amplitude whereby a choice
of records may be made as the negative films

from said cameras are developed for printing sound amplitude may be synchronously recorded onto the tracks as advancement thereof is effected by the recording apparatus.

Associated with amplifying device 4 is a suitable loud speaker 21 preferably located in the monitor room 22, whereby preliminary adjustment of rheostat levers, as 3S, 3M and/or 3L, may be made to suit the particular actors who are to perform.

A motion picture camera, as 9, is suitably driven in synchronism with sound recording cameras 6A, 6N and 6S, preferably by a motor as 8, whereby the sound and action are recorded simultaneously.

Whereas only three adjustments of rheostats 12 are shown, it is to be understood that a greater number may be employed and that rheostats 2S, 2M and 2L may be likewise modified.

It is to be understood that the circuit closers, as 3S, 3M and 3L are located adjacent the action and sound being recorded whereby the operator thereof may have knowledge when said circuit closer should be opened and closed.

It is also to be understood that the modulating devices 2S, 2M, and 2L, although shown adjacent the circuit controllers 3S, 3M and 3L, are assumed to be located in the monitor room 22 and under the control of the operator thereof whereby the circuits to the microphones, as 1S, 1M, 1L, or 40 may be adjusted for the recording of proper amplitude sound records during a rehearsal prior to the final recording.

Whereas the abnormal, normal and sub-normal recording of the sound records in sound records cameras 6A, 6N and 6S has been described as being accomplished by variation of the light intensity of light sources, as 10—10, such recording may be also accomplished by varying the amount of resistance 48 arranged to shunt out a portion of the energy between the light valves of each of said cameras. It will be noted that the sound recording camera 6A, (Fig. 2) is receiving all the energy therethrough, whereas the camera 6N is receiving a lesser amount of energy, the variable resistance 48 positioned between said cameras, acting to shunt out a portion of said energy through resistance 48. It will also be noted that camera 6S is receiving a further reduced amount of energy impulses, the variable resistance between cameras 6N and 6S acting to further shunt out said energy impulses before reaching camera 6S. If desired a combined variable positioning of the levers, as 13—13 to vary the intensity of the source of illumination, and a variation of the resistance 48 to vary the amount of the energy shunted, may be effected.

What I claim is:—

1. Apparatus for recording sound comprising, sound recording apparatus arranged to synchronously advance a plurality of light sensitive photographic sound tracks for recording the sound thereon, an energized circuit including sound responsive apparatus arranged to receive the sound to be recorded, a plurality of light controlling devices associated with the recording apparatus responsive to the circuit including the sound responsive device apparatus arranged to effect recording of the sound onto the sound tracks, a light source for each light controlling device arranged to effect recording of the sound onto the tracks in response to the operation of the light controlling device, and means associated with each light source for adjustably varying the light intensity thereof relatively whereby sound records of differing

onto the tracks as advancement thereof is effected by the recording apparatus.

2. Apparatus for recording sound comprising, a sound responsive device included in an energized circuit arranged to produce electrical oscillations therein in response to sound waves affecting the device, an energized amplified circuit of electrical oscillations formed in response to the flow of the energy in the first named circuit, sound recording apparatus arranged to advance a plurality of sound record tracks, and a plurality of sound recording devices associated with the apparatus arranged in series relation in the amplified circuit, each device being arranged to record a sound record of the oscillations onto a correlated sound track in response to the flow of the energy in the amplified circuit.

3. Sound recording apparatus comprising, an energized circuit including a sound response device arranged to produce electrical oscillations in the circuit in response to sound directed into the device, a second energized circuit including means for amplifying the flow of energy in the first named circuit for producing amplified electrical oscillations in the last named circuit, sound recording apparatus arranged to advance a plurality of sound record members synchronously, and a plurality of sound recording devices associated with the apparatus arranged in series relation in the amplified circuit each device being arranged to record a sound record of the electrical oscillations onto a correlated advancing sound record in response to flow of energy in the amplified circuit.

4. In a system for recording sound, a microphone for receiving the sound including a circuit having the energy therein modulated in response to the sound received by the microphone, an amplifying device including a recording circuit having the energy therein modulated in response to the modulation of the energy in the microphone circuit, a plurality of photographically sensitive sound tracks advanced synchronously, a light valve associated with each sound track for recording sound thereonto, the light valve being connected in series relation in the recording circuit.

5. In a system for recording sound, a microphone for receiving the sound including a circuit having the energy therein modulated in response to the sound received by the microphone, an amplifying device including a recording circuit having the energy therein modulated in response to the modulation of the energy in the microphone circuit, apparatus for advancing a plurality of sound tracks synchronously, a plurality of sound recording devices each arranged to record the sound onto a correlated sound track, and means connecting the devices in series relation in the recording circuit, the series connection thereof formed between each device being independent of any other portion of the recording circuit.

6. In sound recording apparatus for recording waves of differing frequency produced in response to sound, means for advancing a plurality of photographically sensitive sound tracks, means responsive to the waves for photographically recording sound onto certain of the advancing tracks in differing amplitude, and means affecting the recording means for effecting the recording of differing amplitude sound

records having differing photographic intensity on certain other advancing sound tracks.

7. In a sound recording system, a plurality of sources of sound of differing amplitude, a 5 microphone correlated to each source for receiving all the recordable frequencies produced thereby, a source of energy, a normally open circuit connected between each microphone and the energy source, means for varying the flow 10 of energy in each circuit for effecting a normal amplitude flow therein with respect to the amplitude of the sound source correlated thereto, means responsive to the circuits for recording sound onto advancing photographic film, and 15 means selectively closing the circuits for re-recording sound produced by selected sound sources.

8. In a sound recording system, a plurality of sources of sound of differing amplitudes, a 20 microphone correlated to each sound source for receiving all the recordable frequencies produced thereby, a source of energy, a normally open circuit connected between each microphone and the energy source, means for varying 25 the flow of energy in each circuit for effecting a normal amplitude flow therein with respect to the amplitude of the sound source correlated thereto, means for advancing a plurality of sound tracks synchronously, means responsive to each circuit for recording sound onto a selected sound track, and means selectively closing the circuits for recording sound produced by selected sound sources onto selected advancing sound tracks.

9. In a system for recording sound, a plurality of sources of sound of differing amplitude, a microphone for receiving all the recordable frequencies of sound from all the sources, a source of energy, a plurality of normally open circuits 40 connected between the energy source and the microphone, each circuit being correlated to a selected sound source, means in each circuit varying the flow of energy for effecting a normal amplitude flow therein with respect to the 45 amplitude of the sound source correlated thereto, means for advancing photographic film, means responsive to the circuits for photographically recording sound onto the advancing film, and means selectively closing the circuits for 50 recording sound produced by selected sound sources only onto the advancing film.

10. In a system for recording sound, a microphone for receiving the sound including a circuit having the energy therein modulated in response to the sound received by the microphone, an amplifying device including a recording circuit having the energy therein modulated in response to the microphone circuit, sound recording apparatus for advancing a plurality of 55 sound tracks synchronously, a plurality of sound recording devices arranged in series relation in the recording circuit for recording sound onto

the advancing sound tracks, certain of the recording devices having all the energy of the circuit flowing therethrough for recording the sound in one amplitude, and means variably shunting a portion of the energy in the recording circuit around certain other devices for recording sound records of differing amplitude onto other sound tracks as they advance. 80

11. In a sound recording system, a microphone for recording the sound including a circuit having the energy therein modulated in response to the sound received by the microphone, an amplifying device including a recording circuit having the energy therein modulated in response to the modulation of the energy in the 90 microphone circuit, sound recording apparatus for advancing a sound track, a sound recording device for recording the sound onto the sound track in a predetermined amplitude in response to the modulated energy flow in the recording 95 circuit, and means affecting the recording device for varying the amplitude of the sound record recorded thereby independently of the modulated energy flow in the recording circuit.

12. In sound recording apparatus, means for 100 advancing a plurality of photographically sensitive sound tracks, synchronously, a light valve associated with each sound track for recording sound thereonto in response to modulated energy actuating the light valves, a source of 105 light for each light valve, and means independently varying the light intensity of each light source.

13. The method of recording sound which involves, advancing a plurality of photographically sensitive sound record tracks and during the advancement photographically recording the sound onto a selected track with one light intensity simultaneously with photographically recording the same sound onto other selected 115 tracks with differing light intensities.

14. The method of recording sound which involves, advancing a plurality of photographically sensitive sound record tracks and during the advancement photographically recording the 120 sound onto a selected track in one amplitude and with one light intensity simultaneously with recording the same sound onto other selected sound tracks in other amplitudes and with other light intensities. 125

15. The method of recording sound which involves, producing sound of varying frequency, advancing a plurality of photographically sensitive sound record tracks synchronously, and during the advancement thereof photographically recording all the sound produced onto certain tracks in differing amplitudes simultaneously with photographically recording the differing amplitude records onto certain other tracks in differing photographic intensity. 135

OSCAR A. ROSS.
